(57) **CLAIM**

The ornamental design for a bird repellent device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a bird repellent device; FIG. 2 is a rear elevational view of the bird repellent device; FIG. 3 is a left side elevational view of the bird repellent device;

FIG. 4 is a right side elevational view of the bird repellent device;

FIG. 5 is a top plan view of the bird repellent device;

FIG. 6 is a bottom plan view of the bird repellent device;

FIG. 7 is a top perspective view of the bird repellent device; and,

FIG. 8 is a bottom perspective view of the bird repellent device.
